Attorney

UNITED STATES PATENT OFFICE.

CHARLES O. EWELL, OF DYER, TENNESSEE.

SHIPPING CRATE.

Application filed August 17, 1922. Serial No. 582,445.

To all whom it may concern:

Be it known that CHARLES O. EWELL, a citizen of the United States, residing at Dyer, in the county of Gibson and State of Tennessee, has invented certain new and useful Improvements in Shipping Crates, of which the following is a specification, reference being had to the accompanying drawings.

10 This invention relates to crates or hampers for the shipment of fruits and vegetables and has for its object the provision of a novel crate which is capable of being shipped in knocked down condition to be subsequently set up or assembled by the user, the advantage being that a great saving will be effected in transportation charges.

15 The important and more specific object is the provision of a crate of this character which consists of a plurality of panels, preferably slatted and permanently secured in proper relation by wire or other flexible means, the panels being readily capable of being brought to shape and secured by twisting the free ends of the wire together to define a receptacle, a removable top and bottom being also provided which will operate to maintain the receptacle in proper shape.

20 An additional object is the provision of a crate of this character which will be simple and inexpensive in manufacture, efficient in use and a general improvement in the art.

25 With the above and other objects and advantages in view the invention consists in the details of construction to be hereinafter more fully described and claimed and illustrated in the accompanying drawings in which:

30 Figure 1 is a perspective view of the device in set up position;

Figure 2 is a vertical section;

Figure 3 is a horizontal section;

35 Figure 4 is a plan view with the cover broken away; and

40 Figure 5 is a plan view showing all the panels flattened out and lying in the same plane.

45 Referring more particularly to the drawings, I have shown my crate as consisting of four similar panels 10 which might be formed solid but which are preferably constructed of slats 11 secured to upper and lower transverse cleats 12 and 13, respectively, which extend entirely across the panel and which have mitered ends 14. The panels are here illustrated as being of

trapezoidal shape though they could be rectangular if preferred. It should be mentioned in passing that the upper cleats 12 are spaced slightly from the wider ends of the panels as clearly illustrated.

50 All the panels 10 are secured to two or more flexible members such as the wires 15, the securing being effected as by means of staples 16 driven into the slats 11 preferably at the points where the slats engage the cleats. Ordinarily two cleats are sufficient for each panel and two wires provide sufficient strength. If desired, however, the panels might be provided with more cleats and more than two wires may be used though naturally the smaller number is preferable as reducing the cost of production.

55 The device further includes a rectangular bottom 17 which seats upon the lower cleats 13 when the crate is assembled and which is preferably reinforced by transverse cleats 18.

60 The numeral 19 represents the top or cover which is likewise rectangular and which may be either solid or slatted and reinforced by cleats 20. This top is of such size as to fit upon the upper edges of the cleats 12 naturally within the confines of the projecting upper ends of the panels. Any preferred securing means may be provided for holding the top in place.

65 Initially, or at any time when the crates are shipped empty, the four panels are laid flat with the top and bottom members 17 and 19 lying at any convenient point thereon, this arrangement permitting the shipment of a large number of crates in a comparatively small compact bundle. When it is desired to set up a crate for use the four panels are swung to define the enclosure and the ends of the wires 15 are twisted tightly together as indicated at 21, after which the bottom 17 is inserted to maintain the shape. 70 Owing to the fact that the ends of the cleats 12 and 13 are mitered it is apparent that they will engage and exert a mutual bracing action which will further assist in holding the shape. After the crate is thus set up it is, of course, filled in the usual manner and the cover is placed in position.

75 From the foregoing description and a study of the drawings it will be apparent that I have thus provided a simply constructed and consequently inexpensive crate which is highly advantageous in use in the

same capacity as the ordinary round basket or hamper while having the superior feature of being capable of being shipped in knocked down form so that a large number 5 may be piled together and secured to form a compact bundle, this naturally reducing transportation charges.

While I have shown and described the preferred embodiment of the invention, it is, 10 of course, to be understood that I reserve the right to make such changes in the form, construction and arrangement of parts as will not depart from the spirit of the invention or the scope of the subjoined claim.

15 Having thus described my invention, I claim:

A shipping crate comprising a plurality of similar panels, each including spaced slats connected by upper and lower cleats 20 having mitered ends, each panel being narrower at its lower end than at its upper end,

wires secured to all of the panels and having their ends initially free and projecting beyond the edges of the endmost panels, said panels being arranged to define a receptacle and the free ends of the wires being twisted together to retain the receptacle in shape, the mitered ends of the cleats respectively engaging against each other to thereby brace the receptacle, and a top and bottom disposable against said cleats, the bottom being disposed within the receptacle and resting upon the upper faces of the lower cleats and holding the top of the crate expanded, the top resting upon the upper set 30 of cleats, both the top and bottom having transverse cleats adapted to fit inside of the top and bottom cleats of the crate.

25 In testimony whereof I hereunto affix my signature.

CHARLES O. EWELL.
